UNITED STATES PATENT OFFICE.

BENJAMIN F. KELSEY, OF MINNEAPOLIS, MINNESOTA.

CYLINDER-LUBRICATOR.

SPECIFICATION forming part of Letters Patent No. 640,773, dated January 9, 1900.

Application filed October 3, 1898. Serial No. 692,488. (No model.)

To all whom it may concern:

Be it known that I, BENJAMIN F. KELSEY, a citizen of the United States, residing at Minneapolis, in the county of Hennepin and State 5 of Minnesota, have invented certain new and useful Improvements in Cylinder-Lubricators; and I do hereby declare the following to be a full, clear, and exact description of the invention, such as will enable others skilled 10 in the art to which it appertains to make and use the same.

My invention has for its object to provide an improved lubricator-feeding device for cylinders.

15 It relates particularly to that class of lubricator-feeding devices usually styled "choke-feed" lubricators, and it is adapted for use in connection with locomotives or stationary engines.

20 The choke-feed devices now in general use on cylinder-lubricators will effect the feed of the oil to the valve-chest and cylinders in sufficient quantities as long as there is sufficient difference of pressure in the lubricator 25 and in the cylinder-pipe. Otherwise stated, as long as the throttle-valve is partly closed the ordinary choke-feed will supply the needed oil; but if the throttle be wide open, as when the engine is drawing a heavy load on a steep

30 grade, or for any other reason, the pressure in the valve-chest and cylinder-pipe will approximate so closely to that in the lubricator that sufficient oil will not be fed through the ordinary choke-feed. Still otherwise stated, 35 if the contracted passage in the choke-feed be adapted for the desired supply of oil when working the engine with the steam more or less throttled the lubricator will not supply sufficient oil when the throttle is wide open.

40 The extreme difficulty in securing the proper feed of oil into the cylinder and steam-chests when the throttle-valve is wide open and the engine doing hard work, with the result that the pressure in the steam-chests closely approximates the pressure in the lubricator, is 45 due to back pressure against the feed of the lubricator caused by the impulses or intermittent increases in pressure while this approximation of pressures exists under the above 50 conditions.

One of the salient features of my invention is directed to a device or devices which act to

convert or turn a portion of the pressure due to the impulses into a reacting force which tends to strengthen or supplement the normal 55 feed. More specifically stated, I provide a by-passage having a relatively large receiving extremity subject to the pressures from the impulses and having a contracted nozzle or delivery end arranged to discharge within 60 the oil-delivery passage in the direction of the feed of the oil.

Another feature of my invention consists in the provision of a device whereby an increased pressure per square inch is put upon the oil 65 over and above the pressure of the steam which acts directly or indirectly to force the oil from the oil-containing receptacle.

In addition to the features above noted my invention comprises novel features of construction to be hereinafter specifically noted; and, broadly stated, my invention consists of the novel devices and combinations of devices 70 defined in the claims.

Obviously my invention has for its object 75 to provide an improved device of the character above noted which will be free from certain defects found in prior devices.

My invention is illustrated in the accompanying drawings, wherein like characters indicate like parts throughout the several views.

Figure 1 is a view in side elevation with some parts broken away and others shown in section, illustrating the preferred form of my improved lubricating device and its connections to the steam-chest of an engine. Fig. 2 is a front elevation with some parts broken away and others removed, showing the lubricator-feeding device illustrated in Fig. 1. Fig. 3 is a detail view in plan of a part of the 80 device, other parts being removed and the positions of the cylinders being illustrated by dotted lines; and Fig. 4 is a detail view, partly in side elevation and partly in vertical section, showing the feed-valve. 85

1 indicates the cylinder, 2 the steam-chest, and 3 the valve-stem, of a locomotive or other engine. In this preferred construction the lubricating device comprises a pair of cylinders *a* and *b*, which are located side by side 90 and are secured to a common base-bracket *c*. The cylinder *a* receives the steam, and the cylinder *b* is adapted to receive and contain a body of lubricating-oil *z*. Piston-heads *a'* 95

and b' , respectively, work in the cylinders a and b and are provided, respectively, with piston-rods a^2 and b^2 , that work in the ordinary manner through suitable stuffing-boxes formed in the respective cylinder-heads. At their outer ends the piston-rods a^2 and b^2 are provided, respectively, with racks a^3 and b^3 , that have dovetailed grooves in their backs or outer edges and in which dovetailed guides c' of a supporting-bracket c^2 work to guide said racks for true vertical movements. The supporting-bracket c^2 has a central depending portion c^3 , which is rigidly secured to and between the cylinders a and b . A spur-wheel d , mounted on a stud or pin projection d' from the supporting-bracket c^2 , is in mesh with both racks a^3 b^3 , and the said racks are so set with respect to each other that the piston-heads a' and b' will be simultaneously moved to their extreme positions in the opposite ends of their respective cylinders. It should be here noted that the cylinder a and its piston-head are of greater diameter than are the cylinder b and its piston. From this it of course follows that the aggregate pressure on the piston-head a' from the steam will equal the aggregate resisting pressure on the piston-head b' from the oil, and consequently that the pressure per square inch on the oil will be in excess of the pressure per square inch of the steam within said cylinder a . This, as will later more clearly appear, insures the feed of the oil into the cylinder and steam-chest.

35 A steam-supply pipe e , which leads from the boiler or other suitable source of supply, opens into the bottom of the cylinder a . As shown and preferred, this pipe e is provided with an ordinary globe valve e' , and the cylinder a is shown as provided with a drip-cock e^2 .

Oil is introduced into the cylinder b while the piston-head b' is raised through a neck or tubular section f , that opens into the bottom 45 of said cylinder and is provided at its upper end with a funnel-shaped mouth f' , adapted to be opened and closed by a hand-valve f^2 .

The oil-delivery pipe or tube g opens from the bottom or lower portion of the cylinder b 50 and leads to and opens into the steam-chest 2 of the engine. At this point it may be stated that this oil-delivery pipe g instead of opening directly into the steam-chest might open directly into the steam-supply pipe, which in 55 turn opens into the cylinder. As shown, this oil-delivery pipe g involves a tubular glass section g' , which is coupled so as to form a part of said oil-delivery tube or pipe by union or joint sections g^2 . The upper union or joint 60 section g^2 forms an elbow between one section of said delivery-tube g and said glass section g' , and it is provided with a capillary or contracted oil-passage g^3 , which is adapted to be opened and closed by a hand-set needle-valve g^4 . Also, as shown and preferred, the 65 union-section g^2 is provided with a nipple-like dropper g^5 , which surrounds the capil-

lary passage g^3 and depends therefrom into the glass or transparent tube g' .

At its delivery end the oil-delivery tube g is 70 provided with a contracted passage g^6 , which, as shown, is formed by a bushing or perforated plug g^7 . A return tube or passage g^8 opens at its large end into the steam-chest 2 and is extended into the delivery end of the 75 feed-tube g , wherein it terminates in a nozzle-section g^9 , which is positioned to discharge in the direction of the feed of the oil directly into the contracted passage g^6 . As shown, this return or reaction tube g^8 is formed in 80 two sections, which are connected by a union-joint g^{10} .

Another device which operates in very much the same manner as the device just described is preferably located farther forward 85 in the feed-tube g . This device, as shown and preferred, comprises a return or reaction passage g^{11} , which is formed integral with a section g^{12} of the feed-tube g . The larger receiving end of this passage g^{11} is located farther onward than its smaller end. Between the large and small extremities of said passage g^{11} the feed-tube g is provided with a contracted nipple or nozzle section g^{13} , and the smaller end of said passage g^{11} terminates in 95 a similar nipple or nozzle section g^{14} . The nozzle g^{14} is positioned to discharge directly into the nozzle g^9 in the direction of the feed of the oil, and preferably the passage through the nozzle g^{13} is slightly larger than that through the nozzle g^{14} .

Operation: The operation, briefly summarized, is substantially as follows: As previously stated, the oil is fed from the oil-containing cylinder or cup b under a pressure in 105 excess of that of the steam-pressure in the motor-cylinder a . By regulating the valve g^4 the flow of the oil may be increased, decreased, or entirely shut off. The action of the reaction-tube g^8 will now be described, and this will suffice also for a description of the action 110 of the similar passage g^{11} , located farther ahead in the feed-tube g . As near as I have been able to determine this action will be substantially as follows: Under the impulses of 115 pressure within the steam-chest 2 the steam will find a much more rapid escape through the large receiving end of the reaction-passage g^8 than it does through the much smaller passage g^6 in the plug g^7 of the feed-pipe, and hence an instantaneous forced draft will be 120 blown through the nozzle g^9 and thence through the passage g^6 in the direction of the feed of the oil. In this manner the force of 125 the impulses of pressure which would tend to retard the flow of the oil is made to react in such manner as to assist in the feed of the oil into the cylinder. It is also obvious that the greater are these impulses of pressure the greater will be their reacting force to assist 130 the feed. Of course it is not claimed that under steady pressure the reaction-passages would act in the manner above described. They simply convert the impulses of pressure

into instantaneous reacting forces. The reaction-passage g^{11} and its coöperating parts act as an auxiliary device to reinforce the action of the other similar device.

5 In the illustration given a single feed-tube leading from the oil-cylinder to a single steam-chest is shown; but on a locomotive or other two-cylinder engine two such feed-tubes would of course be provided.

10 What I claim, and desire to secure by Letters Patent of the United States, is as follows:

15 1. In a lubricator-feeding device, the combination with a pair of differential-feed motors parallel with and spaced apart from each other, of steam or similar connections leading to the low-pressure motor, an oil-passage or similar connection leading from the high-pressure motor to the device to be lubricated, and an intermediate device pivoted to a suitable support and connected to the movable parts of said two motors, the arrangement being such that the pressure per square inch within the oil-containing motor will exceed that within the companion motor, substantially as and for the purposes set forth.

2. A choke-feed device for lubricators, comprising an oil-supply tube or passage, and a reaction-passage having a relatively large receiving extremity open to the pressure against which the oil is to be fed and having a contracted discharge end positioned to discharge into said oil-supply tube or passage, in the direction of the feed of the oil, substantially as described.

3. A choke-feed device for lubricators, comprising an oil-supply tube or passage having a contracted section, and a reaction-passage open at its larger end to the pressure against which the oil is fed and having a contracted discharge extremity positioned to discharge directly into the contracted passage of said feed-tube, in the direction of the feed of the oil, substantially as described.

In testimony whereof I affix my signature in presence of two witnesses.
